DESIGN FOR A WHEEL-LOAD SCALE FOR VEHICLES

Henry Dreyfuss, New York, N. Y., assignor to
Fairbanks, Morse & Co., Chicago, Ill., a corpora-
tion of Illinois

Application July 20, 1944, Serial No. 114,466

Term of patent 14 years

(Cl. D52—10)

To all whom it may concern:

Be it known that I, Henry Dreyfuss, a citizen
of the United States, residing at New York city,
in the county of New York and State of New
York, have invented a new, original, and orna-
mental Design for a Wheel-Load Scale for Ve-
hicles, of which the following is a specification,
reference being had to the accompanying draw-
ing, forming part thereof.

In the drawing:

Fig. 1 is a perspective view of the rear of a
wheel-load scale for vehicles showing my new
design;

Fig. 2 is a perspective view of the front of the
scale.

I claim:

The ornamental design for a wheel-load scale
for vehicles, as shown.

HENRY DREYFUSS.
